UNITED STATES PATENT OFFICE.

WALTER M. SHETLER, OF LITCHFIELD, NEBRASKA.

DESIGN FOR A PAIR OF FORCEPS.

50,879.

Specification for Design.

Patented June 5, 1917.

Application filed April 11, 1916. Serial No. 90,511. Term of patent 14 years.

To all whom it may concern:

Be it known that I, WALTER M. SHETLER, a citizen of the United States, residing at Litchfield, in the county of Sherman and State of Nebraska, have invented a new, original, and ornamental Design for Forceps, of which the following is a specification, reference being had therein to the accompanying drawing.

The figure is a side elevation of a pair of forceps, showing my new design.

I claim:—

The ornamental design for a pair of forceps, as shown.

In testimony whereof I affix my signature.

WALTER M. SHETLER.
